UNITED STATES PATENT OFFICE.

HENRY P. CLAUSEN, OF MAMARONECK, NEW YORK, ASSIGNOR TO WESTERN ELECTRIC COMPANY, INCORPORATED, OF NEW YORK, N. Y., A CORPORATION OF NEW YORK.

SIGNALING SYSTEM.

Application filed December 6, 1923. Serial No. 678,937.

To all whom it may concern:

Be it known that I, HENRY P. CLAUSEN, a citizen of the United States of America, residing at Mamaroneck, in the county of 5 Westchester and State of New York, have invented certain new and useful Improvements in Signaling Systems, of which the following is a full, clear, concise, and exact description.

10 This invention relates to signaling systems, and more particularly to such systems in which vacuum tubes or their equivalent form a part.

An object of the invention is to vary the 15 potential applied to the grid and plate electrodes of a vacuum tube without varying the filament current.

In accordance with the above object, the 20 present invention contemplates the provision in the filament circuit of a vacuum tube of a double rheostat having a single control element for changing the potential of the grid or plate electrodes or both without varying the filament current.

25 In the drawing, Fig. 1 illustrates one embodiment of the invention; Fig. 2 shows the circuit connections for causing variations in the potential applied to the plate electrode; Fig. 3 illustrates the circuit connections for 30 causing variations in the potential applied to the grid electrode; while Fig. 4 illustrates a modification of the arrangement shown in Fig. 1.

In Fig. 1 there is shown a radio receiving 35 set consisting of a stage of radiofrequency amplification, a detector and a stage of audio-frequency amplification with a translating device associated with the stage of audio-frequency amplification.

40 The antenna 5 may be either of the aerial type or the loop type. The antenna 5 is grounded through an adjustable condenser 6, an inductance 7, and the primary winding of an adjustable inductive coupling 8. Connected to the secondary winding of the inductive coupling 8 is a thermionic device 9 serving to amplify the waves of the radio frequency. In order to improve the selectivity of the circuit, thus allowing its use 45 with all wave lengths, an adjustable condenser 10 is connected in the input circuit of the thermionic device 9.

50 Inductively coupled through a transformer 14 is a thermionic device 15 which 55 functions as a detector or rectifier of the

waves of the radio frequency impressed thereon through the operation of the thermionic device 9. In addition to the thermionic devices 9 and 15, a third thermionic device 19 is inductively connected to the 60 thermionic device 15 by means of a transformer 18. The thermionic device 19 is adapted to amplify the detected or rectified signals; i. e., it serves as an amplifier for the audio-frequency signals. Connected in 65 the output circuit of the thermionic device 19 is a translating device, preferably a telephone receiver 20.

Each of the thermionic devices 9, 15 and 70 19 is of the three-element type; i. e., each is provided with a filament 21, a grid or control electrode 22, and a plate electrode 23. The filaments of each of the thermionic devices are heated by parallel connections from a battery 24, while potential for the 75 plate electrodes of the various tubes is supplied from a battery 25 which has various taps for giving the desired potentials to the respective thermionic devices.

Connected in each of the filament circuits 80 is a double rheostat with a single control element. Each of these rheostats comprises a pair of resistances 26 and 27 and a pair of spring members 28 and 29. These spring members are suitably fastened to a supporting member 30 which may be moved in order 85 to vary the resistances 26 and 27. It is apparent from the drawing that should the supporting member 30 be moved, say in an upward direction, the resistance in the filament circuit will be maintained constant. Although the movement of the supporting member 30 in an upward direction increases 90 the amount of resistance 26 connected in the circuit, a corresponding decrease in the resistance 27 results. Consequently, the current in the filament 21 is maintained constant. However, the movement of the supporting member 30 in this manner varies 95 the potential applied between the filament 21 and the grid electrode 22 as well as between the filament and the plate electrode 23.

When the spring members 28 and 29 are in their lowermost position, all of the resistance 26 is disconnected while all of the 100 resistance 27 is connected in the filament circuit. In this position of the switch, the potential difference between grid and negative end of filament is equal to the drop in 105 resistance 27. Now in the case of the plate 110

electrode 23, since all of the resistance 27 is connected in the filament circuit, the potential of this electrode with respect to negative end of the filament will be at the potential of the plate battery plus the drop in the filament. It is thus seen that when the supporting member 30 is moved so that the grid electrode 22 becomes less negative, the plate electrode 23 is in turn made more positive and vice versa. The same result is obtained by operating the rheostats in the amplifiers 9 and 19.

In the case of detector devices, it is desirable to work on the most critical part of the curve characteristic, that is, at a point where the largest difference in amplification is produced. With the arrangement previously described the potential of the grid electrode may be varied to shift the position on the curve characteristic at which the device is operated, therefore enabling better detection without changing the filament current. At the same time, the potential of the plate electrode is varied dependent on whether the grid is made more or less negative. With regard to the amplifier devices 9 and 19, the best operating condition results when they are operating on the point of the curve characteristic having the greatest slope. If it is discovered that the device is not operating on the most efficient part of the curve characteristic, the potential of the grid electrode may be varied to bring about the most satisfactory operating condition.

Referring now for the moment to Fig. 2, a vacuum tube 32 having a cathode 33, a grid electrode 34 and a plate electrode 35, is inductively connected to an antenna 36 by means of an adjustable inductive coupling 37. Apparatus similar to that described in connection with Fig. 1 is included in the antenna circuit as well as a condenser in the secondary circuit of the inductive coupling. In the arrangement shown in this figure, however, the grid electrode 34 is connected to a resistance 38 which is connected between the terminals of the filament 33 and which is connected to the spring members of a rheostat 39 identical to that described in connection with the thermionic device 15. The plate electrode 35 of this thermionic device 32 is connected through telephone receivers 40 to the positive pole of battery 41 and to the right hand resistance of the rheostat 39. When the rheostat 39 is moved in an upward direction, the filament current is maintained constant, while the grid electrode 34 is maintained at a potential corresponding to the potential of the filament. However, in the case of the plate electrode, the potential is varied in accordance with the changes in the right hand resistance of the rheostat 39. With such an arrangement, the potential of the plate electrode may be varied

without producing any change in the filament current or in the potential difference between the grid and the filament. The grid connection to the resistance 38 is intended merely as a schematic showing representing any desired constant potential relation between the grid and the filament.

Fig. 3 is similar to the arrangement shown in Fig. 2 except that the thermionic device 42 is arranged with respect to a rheostat 43 so that the potential of the grid electrode is varied in accordance with the changes in the left hand resistance of the rheostat 43. The plate electrode of the thermionic device 42 is connected to a resistance 44 connected between the terminals of the filament of this device, and a constant difference of potential is maintained between the plate and filament.

The arrangement shown in Fig. 4 is a modification of that shown in Fig. 1. Owing to the high potentials applied to the plate electrodes of the thermionic device or devices employed for audio-frequency amplification, it is desirous to apply to the grid electrode of such a device a correspondingly high potential. In this figure, the filaments of the thermionic devices 46, 47 and 48 are connected in series with a battery 49, the filament of the thermionic device 47 being connected to the positive end of the battery 49. As in the previous illustrations, there is connected in the filament circuits of each of the thermionic devices 46, 47 and 48 a double rheostat 50, 51 and 52, respectively. The grid electrode of the thermionic device 46 is connected to the negative pole of the battery 49 and the left hand resistance of the rheostat 50, the potential drop between the grid and filament being determined by the amount of this resistance which is connected in circuit. The grid electrode of the thermionic device 48 is also connected directly to the negative pole of the battery 49. With such an arrangement, the potential between the grid and filament of the thermionic device 48 is not only dependent upon the effective resistance of the rheostat 52, but is also dependent upon the effective resistance of the rheostat 50 and of the filament of device 46. It is thus seen that by the use of such controlled means a much higher potential can be obtained on the grid electrode of the thermionic device 48 than would be obtained if the grid electrode was connected to the left hand resistance of the rheostat 52. Furthermore, on account of the self-compensating feature of the rheostats the bias of each grid may be regulated without affecting the bias of the other grids. The potentials of the plate electrodes of each of the devices is also varied in a manner similar to that already described.

Although the invention has been disclosed

and described with reference to particular circuit arrangements, it is of course obvious that various modifications and adaptations may be made without departing from the 5 spirit and scope of the present invention.

What is claimed is:

1. In combination, a vacuum tube having a cathode, a control and a plate electrode, a source of potential for said tube, and means included in the cathode circuit for effecting changes in the potentials applied to said control and plate electrodes without changing the current in the cathode circuit. 10
2. In combination, a vacuum tube having a cathode, a control and a plate electrode, a source of potential for said tube, a double rheostat included in the cathode circuit, and a single control element for changing the resistance of said rheostat to effect changes 15 in the potential applied to the control and plate electrodes without changing the current in the cathode circuit. 20
3. In combination, a vacuum tube having a cathode, a grid and a plate electrode, a source of potential for said cathode, a resistance in series with said cathode and means for varying said resistance so that the potential applied to said control electrode may be varied without causing a 25 change in the current through said cathode. 30
4. In combination, a vacuum tube having a cathode, a grid electrode and an anode, a source of potential for said cathode, a pair of rheostats in series with said cathode, and a single control element for simultaneously 35 varying one of said rheostats in accordance with the change in the potential applied to the grid electrode as determined by said other rheostat. 40
5. In combination, a multi-stage vacuum tube amplifier, each of said amplifiers having a cathode, a grid and a plate electrode, a source of potential included in the cathode circuit of each of said vacuum tubes comprising a double rheostat, and a single control element for said rheostats for varying the potential applied between said cathode and said grid electrodes and for maintaining the current in said cathode circuit constant. 45
6. In combination, a multi-stage vacuum tube amplifier, each of said amplifiers having a cathode, a grid and a plate electrode, a source of potential, means included in the cathode circuit of each of said vacuum tube amplifiers comprising a resistance serving to determine the fractional part of the source of potential to be applied between said cathode and said grid electrode, a resistance serving to adjust the cathode current, and means common to said resistances for maintaining the cathode current constant irrespective of changes in the potentials applied to said grid electrode. 50
7. In combination, a multi-stage vacuum tube amplifier, each of said amplifiers having a filament, a grid and a plate electrode, a source of potential, the filaments of each of said tubes being serially connected with said source of potential, a double rheostat 55 associated with each of said filaments for changing the potential applied between the grids and the filaments without varying the filament current, and circuit connections for applying a potential between the grid electrode and the filament of one tube due both to the resistance of the associated rheostat and the resistance of the rheostat of another tube independent of changes in the resistance of the rheostat of said other tube. 60

In witness whereof, I hereunto subscribe my name this 28th day of November, A. D., 1923.

HENRY P. CLAUSEN.
